(57) **CLAIM**

The ornamental design for a high drain loop bracket, as shown and described.

DESCRIPTION

FIG. 1 is a top perspective view of a high drain loop bracket; FIG. 2 is a bottom perspective view of a high drain loop bracket;

FIG. 3 is front view of a high drain loop bracket;

FIG. 4 is a rear view of a high drain loop bracket;

FIG. 5 is a top view of a high drain loop bracket;

FIG. 6 is a bottom view of a high drain loop bracket;

FIG. 7 is a left side view of a high drain loop bracket; and,

FIG. 8 is a right side view of a high drain loop bracket. The broken lines depict portions of the high drain loop bracket that form no part of the claimed design.

1 Claim, 5 Drawing Sheets
